UNITED STATES PATENT OFFICE

2,247,438

ELECTRIC SADIRON

Clyde B. Gorton, Chicago, Ill., assignor to Super
Manufacturing Co., Chicago, Ill., a corporation
of Illinois

Application July 13, 1940, Serial No. 345,269

4 Claims. (Cl. 38—77)

This invention relates generally to electric sadirons and more particularly to a sadiron adapted to be used either in connection with steam producing means whereby the steam may be extravasated through the sole of the sadiron as in pressing or steaming apparel and the like, or in the conventional dry pressing methods.

A primary object of this invention is to provide a novel construction for an electrically heated sadiron adapted to be used in connection with a steam generator supplying steam thereto during the pressing or steaming operations.

A further object of this invention is to provide a sadiron of the character described which will be immediately convertible from a steaming iron to a conventional dry pressing iron and vice versa.

A further object of this invention is to provide a combination of steam generating means adapted to feed a sadiron which will be small in size, efficient in operation and adapted for portable household use.

Further objects of the invention lie in the provision of novel means for heating or superheating the steam which is delivered through the sadiron and removing moisture therefrom; novel means for maintaining the high temperature of the front apex of the sadiron; novel and simple construction of the sadiron to assure efficient operation thereof; novel means for preventing the inclusion of moisture within the steam delivered by the steam unit.

An important object of this invention is to provide apparatus of the character described which will be simple in construction, efficient and economical in operation, and which will be adaptable for low-cost production in large quantities.

With the foregoing and other objects in view, which will appear as the description proceeds, the invention consists of certain novel features of construction, arrangement and combination of parts hereinafter fully described, illustrated in the accompanying drawing, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the accompanying drawing a preferred embodiment thereof, from an inspection of which, when considered in connection with the following description, my invention, its mode of construction, as-

sembly and operation, and many of its advantages should be readily understood and appreciated.

Referring to the drawing in which the same characters of reference are employed to indicate corresponding or similar parts throughout the several figures of the drawing:

Fig. 1 is a perspective view of an embodiment of my invention in use and showing the steam generating unit associated with a conventional ironing board, the sadiron, and the connecting cable.

Fig. 2 is a longitudinal sectional view of the sadiron taken through the superheating chamber.

Fig. 3 is a detailed plan view of the front portion of the iron with portions thereof in section showing the front steam chamber.

Fig. 4 is a sectional view of a detail of the sadiron taken generally along the line 4—4 of Fig. 2.

Generally speaking, the invention consists of an improved construction for an electrically heated sadiron having a novel connection with a separately maintained steam generator whereby steam may be generated in large quantities and at suitable temperatures within the steam generator under favorable conditions and conducted to the sadiron for use therein. I provide means whereby the sadiron may be used without the steam in the manner of conventional sadirons. Further, I provide the steam generator with novel means whereby it may be conveniently attached to an ironing board or the like, in any manner, for advantageous use in connection with my sadiron.

Figure 1 shows the arrangement of the apparatus of my invention in use. The reference character 10' designates generally an ironing board of any conventional type having the steam generator 12 clamped thereto by means of the clamping member 13 which is attached to the upper wall of the generator 12. Obviously any horizontally disposed support such as for example a table or the seat of a chair may be used to support the generator. Further, where necessity requires, the clamp may be adjustable so that the generator may be attached for use to an upright support such as the back of a chair and the like.

The sadiron is generally designated by the reference character 10 and it is connected to the steam generator 12 by means of a cable or sheath 11 which will be presently described in detail.

The cable 11 passes through the eye end of a support member 9 which may be secured to the

steam generator 12 or directly connected to the supporting board 10'. The support member 9 may take any convenient form, the type shown being for illustrative purposes only.

The sadiron 10 may be practically any conventional construction, it being noted that I require only slight modification over models presently manufactured and sold commercially. A sole plate 14 is provided having the usual pointed front end or apex and having a casing disposed thereon supporting a handle 16 secured thereto in any well known manner, such as for example by welding or the like. Forwardly disposed of the base plate 14 are a plurality of steam ports 19 for discharging the steam from the sadiron upon the work which is being pressed. The upper ends of the ports 19 open up to a substantially triangularly shaped steam recess 17 formed in the upper surface of the plate 14 and completely enclosed by means of a conformingly shaped plate member 18 secured to the plate 14 directly over the recess 17 by screws or the like.

The plate member 18 is provided centrally thereof with an upstanding boss 20 by means of which steam may be led into the recess 17. The ports 19 are distributed about the floor of the recess 17 away from the point where steam which is discharged through the boss 20, in a manner presently to be described, will impinge. Thus, it is seen that the single stream of steam discharged into the recess 17 will be broken up and distributed to the openings leading to the ports 19 and subsequently be extravasated in uniform and efficient manner.

Immediately disposed upon the upper surface 35 of the plate member 14 and substantially covering the entire extent thereof I have provided a heating element 22 of any convenient construction such as for example having upper and lower sheets 23 of insulating material such as mica or asbestos and a cover plate 24. The element is secured to the plate in any well known manner. In order to assure even heating of the entire sole plate 14 and especially to provide for the heating of the extreme front end of the sadiron, I utilize a heating element having a notch or opening 24' therein at the extreme front end thereof which extends over the plate member 18 of the recess 17 and permits the boss 20 to extend therethrough. While I have shown the opening as a notch, it is obvious that it could as well be a hole in the element 22 through which the boss 20 is adapted to extend thus permitting portions of the heating element to extend to the geometrical tip of the inner surface of the sole plate 14. I have found, however, that the arrangement shown in the drawing gives satisfactory results.

It should be obvious from the above explanation that the upper edge of the plate member 18 should be either flush with or below the surface of the plate member 14 in order to assure correct lying and positioning of the heating element. The arrangement described places portions of the heating element in very close proximity to the recess or chamber 17 into which the steam is finally discharged prior to extravasation through the ports 19. Thus the steam loses none of its heat by being discharged into the chamber 17, but on the contrary, takes on heat which aids in the efficiency of operation of the sadiron. The recess in effect serves as a heater.

The boss 20 is provided with a conduit 21 attached thereto which conduit leads to a bi-chambered receptacle 25 disposed within the casing

15 of the sadiron to one side of the thermostat 32 as shown in Fig. 4. The receptacle is disposed upon the heating element 22 upon the upper plate 24 thereof and hence, is subject to the highest temperatures generated by said element. Thus, steam which may enter the chambers of the receptacle will be heated to high temperatures and will have any moisture contained therein removed and vaporized. The receptacle in effect serves as a superheater.

The receptacle 25 is divided into a front chamber and rear chamber by means of the partition or wall 26 separating and dividing the interior thereof. The conduit 21 enters the front chamber 15 and steam contained therein may pass through the openings 27 formed in the conduit and out through the ports 19 of the sadiron in the manner described above. Live steam is fed from the steam generator through the conduit 20 31 of the cable or sheath 11 to the steam pipe 28 which is secured to the casing 15 leading therethrough. The conduit or steam pipe 28 leads into the rear chamber of the receptacle 25 as shown in Fig. 2 and is provided with openings 30 which permit the flow of steam into the chamber. The ends of the tubes 21 and 29 which are disposed within the respective chambers of the receptacle may or may not be open since the steam will be permitted to pass by means of the laterally disposed openings 27 and 30. However, I prefer to have the ends open.

It will be seen that the steam which enters the receptacle from the steam generator will circulate therein and be superheated by reason of the proximity of the heating unit 22, will then pass through the perforations 28 of the baffle or wall 26 and into the front chamber of the receptacle. Thence the steam will pass into the conduit or tube 21 and finally out through the ports 19.

The sadiron 10 is provided with a thermostat 32 of any suitable construction adjustable by means of a pivoted knob 36 extending out from the upper wall of the casing 15 in convenient disposition adjacent the hand and fingers of the operator. Obviously the thermostat controls the iron temperature. The thermostat 32 and heating element 22 are electrically associated in a well known manner and have electrical leads 33 and 34 leading to an external connection or plug 35 disposed upon the casing 15 at the rear thereof. A rearward extension 37 of the casing is utilized in well known manner to stand the iron on its heel when same is not being used or when the sadiron is being used to steam hats or the like.

It will be noted from the above description that the steam is brought to the sadiron 10 from outside sources. Hence, the iron can be made smaller and lighter and need not be provided with means for carrying water and the like. Further, since the steam source is not carried upon the sadiron, said source may be relatively larger than the steam chambers of steam sadirons heretofore used and thus make steam available a much longer time without the necessity of stopping to fill the liquid chamber.

The sheath or cable 11 is a unitary construction and may be formed from flexible fabric, rubber and the like. It is provided therein with a steam conduit and the electrical leads which connect with the plug 31. The advantages of this single cable construction should be apparent.

The electrically heated generator 12 which I have illustrated is provided with a filling mecha-

nism 42 and, as previously explained, is adapted to be attached to the ironing board by means of the clamp 43. An electric cord 61 extends from the generator to a wall outlet or the like, for supplying a current to the iron and the generator. I prefer that the iron and generator be connected in parallel with individual switches so that the generator heating element may be disconnected without affecting the electrical connection of the sadiron itself. Thus, the iron 10 may be used as any conventional iron and without steam, it being obvious that heat control is possible by means of the thermostat 32.

It will be apparent from the above that the objects of the invention have been attained in 15 a novel and efficient manner.

It is believed that my invention, its mode of construction and assembly, and many of its advantages should be readily understood from the foregoing without further description, and it should also be manifest that while a preferred embodiment of the invention has been shown and described for illustrative purposes, the structural details are nevertheless capable of wide variation within the purview of my invention as defined in the appended claims.

What I claim and desire to secure by Letters Patent of the United States is:

1. In combination, a sadiron having a sole plate, a body supported upon said sole plate, an electrical element for heating said sole plate disposed thereupon within said body, a steam generator removed from said sadiron, means for conducting the steam from said generator into the body for extravasation through the sole plate of said sadiron, means for super-heating the steam at a plurality of points while passing through the sadiron prior to extravasation therefrom, one of said points being on one side of the heating element and a second of said points being on the opposite side of said heating element, the superheating means at said second mentioned point comprising a chamber formed within the forward portion of said sole plate and being in close thermal proximity with said heating element to superheat the steam, and a plurality of steam outlets leading from said chamber for discharging the steam through the said sole plate.

2. In combination, a sadiron having a sole plate, a body supported upon said sole plate, an electrical element for heating said sole plate disposed thereupon within said body, a steam generator removed from said sadiron, means for conducting the steam from said generator into the body for extravasation through the sole plate of said sadiron, means for superheating the steam at a plurality of points while passing through the sadiron prior to extravasation therefrom, one of said points being on one side of said heating element in the body of said iron, and a second of said points being on the opposite side of said heating element and in close thermal proximity therewith, the superheating means at the second of said points comprising a chamber formed adjacent the apex of said sole plate and being adapted to superheat the steam immediately prior to extravasation through said sole

plate, said sole plate being provided with a plurality of steam extravasating ports leading from said chamber.

3. In combination, a sadiron having a sole plate, a body supported upon said sole plate, an electrical element for heating said sole plate disposed thereupon within said body, a steam generator removed from said sadiron, means for conducting the steam from said generator into the body for extravasation through the sole plate of said sadiron, means for super-heating the steam at a plurality of points while passing through the sadiron prior to extravasation therefrom, one of said points being on one side of the heating element and a second of said points being on the opposite side of said heating element, the superheating means at said second mentioned point comprising a chamber formed within the forward portion of said sole plate and in close thermal proximity with said heating element and thereby being adapted to superheat the steam immediately prior to extravasation through said sole plate, said chamber being disposed in the upper surface of the sole plate and being enclosed by a cover member overlying same substantially flush with the upper surface of the sole plate, said heating element having a portion thereof substantially covering all of said cover member whereby the said chamber will receive sufficient heat from the heating element to superheat the steam therein, and steam exhaust ducts leading from said chamber to a point on the lower face of said sole plate adjacent the chamber for permitting the extravasation of said superheated steam from said chamber.

4. In combination, a sadiron having a relatively thin sole plate, a body supported on said sole plate, an electrical element for heating said sole plate disposed thereupon within said body and covering substantially the complete upper surface of said sole plate, a steam generator removed from said sadiron, means for conducting the steam from said generator into the body for extravasation through the sole plate of said sadiron, means for superheating the steam at a plurality of points while passing through the sadiron prior to extravasation therefrom including means within the body on one side of the heating element and means within the sole plate on the opposite side of said heating element, said last mentioned means comprising a chamber formed within the upper surface of the sole plate at the apex thereof in close thermal proximity with said heating element, a plate member covering said chamber and being disposed flush with the upper face of said sole plate, a conduit connected to said cover plate member and leading from the superheating means within the body of said sadiron and extending through the heating element, said heating element extending over said cover member for heating the chamber within the sole plate, said sole plate being provided with a plurality of steam ports leading out from said chamber through which the superheated steam is adapted to be extravasated.

CLYDE B. GORTON.
